Patented Aug. 30, 1955

175,474

SIGNAL LIGHT

John J. Manning, Grosse Pointe, Mich.

Application July 29, 1954, Serial No. 31,652

Term of patent 3½ years

(Cl. D72—1)

Fig. 1 is a top plan view of a signal light embodying my new design.

Fig. 2 is a front elevational view thereof;

Fig. 3 is a side elevational view; and

Fig. 4 is a rear elevational view.

The characteristic features of my design reside in the portions shown by means of full lines in the drawing.

I claim:

The ornamental design for a signal light, as shown and described.
